(57) **CLAIM**

The ornamental design for a carrying pack for medical device, as shown and described.

DESCRIPTION

FIG. 1 is a front perspective view of the carrying pack having a belt coupled thereto.

FIG. 2 is a front view of the carrying pack shown in FIG. 1.

FIG. 3 is a rear view of the carrying pack shown in FIG. 1.

FIG. 4 is a top view of the carrying pack shown in FIG. 1.

FIG. 5 is a bottom view of the carrying pack shown in FIG. 1.

FIG. 6 is a first side view of the carrying pack shown in FIG. 1; and,

FIG. 7 is a second side view of the carrying pack shown in FIG. 1.

FIGS. 1-7 are various views of a carrying pack in accordance with the present design. The carrying pack is adapted to be worn on a pack holder's body and to hold a medical device that requires access to the pack wearer's body during use.

Features disclaimed with broken lines in the figures indicate features that form no part of the claimed design. Features disclaimed with dot-dash lines in the figures indicate stitching that forms no part of the claimed design. Features defined by a diagonal cross hatching pattern in the figures indicate an open mesh material of the carrying pack.
